ELECTRON DISCHARGE TUBE

Alexandre Sev, Paris, France, assignor to Compagnie Generale de Telegraphie Sans Fil, a corporation of France

Application January 31, 1934, Serial No. 709,082
In France February 9, 1933

2 Claims. (Cl. 250—27.5)

The present invention is concerned with power amplifiers used in public speaking, talking films, etc., and more particularly symmetric amplifiers known as of the push-pull pattern.

5 It is known that the symmetric coupling of the tubes in push-pull amplifiers allows of eliminating certain distortions due to the curvature or knee of the characteristic curve.

Based upon this principle high-power amplifiers of the so-called class B type have been constructed in which the curved portions of the characteristics are employed. However, it is admitted that the distortions due to the knee are not entirely eliminated by a push-pull scheme.

15 Now, the present invention has as its object a high-power amplifier wherein the distortions due to power tubes connected push-pull fashion are practically obviated. It consists in a novel mode of coupling between the input tube and the power tube next above it. This coupling method allows 20 of eliminating the curved portion in characteristics of power tubes, while maintaining the output or efficiency at a high figure.

A further object of the invention is to provide 25 a normal or fixed bias voltage to the grid of an amplifier tube and means whereby positive signal impulses also are impressed on the grid while the negative signal impulses are substantially prevented from reaching the grid.

30 A still further object is to provide a vacuum tube construction in which a diode having an indirectly heated cathode and a triode having a heated filament are enclosed in the same glass envelope.

35 Other objects of the invention will become apparent to those skilled in the art as the description thereof proceeds. For a better understanding thereof reference is made to the following description taken in connection with the accompanying drawing, in which,

Figure 1 shows the curve of the plate current as a function of the potential of the grid or control electrode in a multi-electrode tube;

Figure 2 shows the coupling of characteristics 45 of a push-pull amplifier of class B, so-called;

Figure 3 represents an embodiment of a coupling forming the object of this invention as applied to a push-pull amplifier;

Figure 4 represents a different embodiment 50 predicated upon the same principle;

Figure 5 represents schematically a double tube adapted to operate in circuits as shown in Figures 3 and 4; and,

Figure 6 illustrates in a general way a mode of 55 coupling as here disclosed.

It will be seen that the characteristic curve of Figure 1 comprises at its lower end a marked curvature or knee. In certain applications, and more particularly in the amplification of telephone currents, it is necessary to suppress the 5 effects of the curvature. Usually recourse is had to two methods, to wit:

(1) In amplifiers belonging to what is called class A the working point (point A, Figure 1) is chosen in a way so that the variations of the plate 10 current I_p will keep inside the limits where $I_p=f(V_g)$ may be regarded as a linear function.

The efficiency of such amplifiers (class A) cannot go beyond 50 percent, but in practice it is rarely ever over 25 percent. 15

(2) In amplifiers of class B, the working point corresponds to a low permanent plate current and is usually located in the curved portion (point B, Fig. 1). To avoid distortions two power tubes are connected symmetrically in phase opposition according to the conventional push-pull 20 scheme.

Figure 2 shows the coupling of the characteristics of two tubes and by broken line the resultant characteristic. The efficiency may exceed 25 60 percent, but the compensation of the curved portions is often incomplete. Whence a distortion is present that will be especially appreciable where low powers are involved.

Now, the method forming the object of the 30 present invention consists in interposing between the input tube or previous stage and the grid of the power tube a circuit comprising an electronic valve, which will permit of the flow to the power grid only of the positive alternation of 35 the potential wave. The working point of the power tube is shifted just above the knee to point C, Fig. 1 by providing a suitable grid bias; and during actual operation it will be able to shift only towards the right-hand side, i. e., into a 40 region where characteristics are sensibly rectilinear.

One arrangement based upon this principle is indicated in Fig. 3 which represents an amplifier 45 for telephone currents of the push-pull type. In the absence of applied signal voltage the valves V_1 and V_2 are negatively biased by virtue of the fall of residual current in or across the resistances R , the value of which is chosen so as to render this current very small or a few microamperes. When the potential V applied to the anode of V_1 is positive the variation of anode current i is practically proportional to V . If R is sufficiently high the ohmic drop across the valve is negligible compared with V . Thus the 50 55

positive alternation of V is transmitted to and impressed upon the control grid 4 of L_1 .

When the voltage V becomes negative, the internal resistance of the valve V_1 grows very fast 5 and the fraction of V transmitted to the grid 4 is very small or negligible. The grid of L_2 is fed in the same way by the valve V_2 . By virtue of the symmetric disposition, the lost voltages of the two alternations are partly compensated.

10 It will be seen that each of the tubes L_1L_2 is operative during an alternation. The curved portions of the characteristics L_1L_2 are suppressed while yet preserving the advantages of amplifiers of class B. As shown, the signal voltage is 15 applied to the control grids by an audio transformer 12 whose primary coils are connected in the plate circuits of tubes 10 and 11. The filaments of tubes L_1L_2 and the heaters 2 of V_1 and V_2 (whose cathodes 2 are indirectly heated) may 20 be heated by alternating current supplied by a transformer 13. The plate current of tubes L_1L_2 may be supplied by a battery or other voltage source 14 connected as shown, and their output may be connected to any translating device such 25 as a loudspeaker 15.

Another circuit scheme predicated upon the same principle is illustrated in Fig. 4. The valve V_1 connected in parallel with the grid of L_1 keeps it at the potential of the common point 30 C during the negative alternation of the voltage. At the same time, the internal resistance of V_2 is infinitely high, and the positive alternation is transmitted and fed to the grid of L_2 , etc.

It may be of advantage in certain circumstances, especially when the reverse current of 35 the grids of L_1 and L_2 is high, to modify the polarization of the valves without affecting R . For this purpose, there may be interposed between O and A (Fig. 3) a biasing battery 16 or else a suitable 40 resistance traversed by a direct current. This current may be furnished from the plate circuit of the input tube or from that of the tubes L_1L_2 by way of two taps on resistance r . It will be noted that the polarization of the power grids 45 (Fig. 3) is obtained automatically by means of the resistance r shunted by a condenser 17 which is the conventional arrangement in the case of amplifiers, class A, but which when applied to the case of amplifiers class B of the normal type 50 is attended with serious difficulties.

It is also feasible to substitute a battery for resistance r .

In Figures 3 and 4 the filaments of the valves L_1-L_2 are heated in parallel with the heaters of 55 the tubes V_1-V_2 , the midpoint 18 of the heating winding being united with the biasing resistor r . In the case of the directly heated valve it is generally necessary to reduce the capacity be-

tween the heating winding and ground by the use of special transformers.

In the embodiments shown in Figures 3 and 4, it is possible to use either valves with a high 5 vacuum or else gaseous valves. It is also possible to substitute multi-electrode tubes for the valves, the characteristics of which present a suitable knee so as to insure a kind of operation as hereinbefore described.

In order to reduce size and space, according 10 to another object of this invention, recourse may be had to a double type of tube comprising the elements of both valve V and power tube L . Such a tube is represented in Figure 5. The two filaments are heated in parallel, the cathode 2 15 of the valve is connected internally with the power grid 4. The number of outlets or prongs is limited to five, all the tube elements being mounted in a single envelope 20.

It is understood that the arrangements of Figures 3 and 4 are cited merely by way of example, for the invention is capable of a great number of modifications as will be evident to those trained in the art. Generally speaking, the coupling arrangement of the invention is 25 shown in principle and in its most abstract form in Fig. 6. The circuit P connected to the plate of the input tube is coupled with the circuit G connected with the power grid by means of a circuit V comprising an electron valve. The coupling between the three circuits is arranged in a way so that the variable potential applied to grid G will not become negative. The working point of the power tube is thus maintained in the linear portion. While shown with an audio amplifier, the same principle may be used in radio frequency amplifiers comprising one tube or two tubes in a push-pull arrangement. 30 35

Having described my invention what I claim as new and desire to secure by Letters Patent is: 40

1. A vacuum tube having an amplifier portion comprising a heatable filament, a grid and a plate, and a rectifier portion comprising a heater, a cathode and a plate, a single envelope enclosing all of the above named elements, connections within the envelope between the filament terminals and the heater terminals and also between the grid and the rectifier cathode. 45

2. An electron discharge tube comprising an evacuated envelope enclosing a filamentary cathode, a grid next adjacent thereto and an anode constituting an amplifier, an indirectly heated cathode and an anode constituting a rectifier, and a direct electrical connection within the envelope between the indirectly heated cathode and the 50 grid. 55
